TYPEWRITING MACHINE

Filed March 5, 1924

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed March 5, 1924. Serial No. 696,923.

To all whom it may concern:

Be it known that I, ALFRED G. F. KUROWSKI, a citizen of the United States, residing in Brooklyn Borough, in the county of Kings, city and State of New York, have invented certain new and useful Improvements in Typewriting Machines, of which the following is a specification.

This invention relates to improvements in typewriting machines, and particularly to devices for holding a card to the platen of the machine.

One of the features of the invention is the provision of a card holder or guide which may readily be attached to and detached from the wing-scale frame.

Another feature of the invention is to provide improved means for holding the card-guide securely on the wing-scale frame.

Another feature is to have the card-guide made of a bar or wire bent to shape and to have the legs of the guide inserted into sockets or apertures in brackets provided for this purpose, and to provide a means for limiting the length of insertion of said legs into said sockets.

Still another feature of the invention is to make the card-guide light and strong, and to have the surface of the guide flaring away from the platen and to serve as a directrix for the edges of the advancing and returning card.

One of the objects of the invention is to avoid trouble from the card-holder wire being accidentally forced out of its seat in the wing-scale structure. The new card-holder wire is supported upon sockets at the sides of the printing point, each socket in the form of a plate. At the bottom of each socket is bent forward an ear in which is formed a perforation, and the links of the card wire extend down through the perforations in top and bottom ears, thus giving a secure anchorage, so that the card wire will not get knocked out or its position disturbed in ordinary use. In the card wire is formed a jog to serve as a stop to limit the thrust of the wire down into the socket.

The card-holder is made of half round wire of relatively large radius, the rounded part being adjacent to the platen, thereby securing a maximum stiffness for the weight

of the wire, and securing the advantage that the surface of the wire flares away from the platen and thereby serves as a directrix for the edges of the advancing and returning card.

The pressure of rolls is transmitted through new brackets to the card-holder itself, which stands close to the front of the platen and bears rearwardly against the wing-scale near the printing point; the card-holder having portions which extend to the right and left from the legs to overlie the wing-scale and press back thereagainst; a bow or U portion of the card wire extending up from these right and left portions. This pressure of the card wire back against the wing-scale is of advantage in holding the card properly against the platen.

Other features and advantages will hereinafter appear.

In the accompanying drawings,

Figure 1 is a front view of the card-holding means shown as situated in front of the platen and with the bearing-roll brackets secured to the type-segment.

Figure 2 is a view, partly in section, on the line 2-2 of Figure 1.

Figure 3 is a view, partly in section, on the line 3-3 of Figure 1.

Figures 4, 5 and 6 are, respectively, a front view, a side view and a plan of the card-guide, showing in dotted lines its shape when its legs are sprung into the brackets, which connect them to the wing-scale frame.

Figure 7 is a detail in section on an enlarged scale of one of the channel-shaped brackets hereinafter described, showing the apertures or sockets contained therein.

11 designates the platen, shown in Figure 2 as supported by the carriage 12 by means of a platen-frame 13 and arms 14. The platen-frame 13 is shown as having connected thereunder rollers 15 riding on a shift-rail 16 of a shift-frame 17, which is pivoted at 18 and actuated by rocker-arms 19.

The wing-scale 20 is shown as situated in the rear of the card guide 21 and connected to the wing-scale frame 22 by means of posts or brackets 43. The wing-scale frame 22 is shown as having the usual cross-rail 23 and the side arms 24, which are in engage-

ment with pins 25 on the shift-frame 17 by means of open bearings 26 at the ends of said arms 24, which are also connected to the shift-frame 17 by means of a spring 27, the ends of which are in engagement with pins 28 and 29 situated respectively on the shift-frame 17 and on extensions 30 of the side arms 24.

The wing-scale frame 22 is shown as having thereon vertical flanges 31, which have therein runways 32 for bearing rolls 33, which have thereon circular flanges 34 to fit into said runways 32, thereby securing the frame 22 against lateral displacement. The bearing rolls 33 are shown as carried by spring bearings 35 which are secured to the type-segment 36.

The wing scale 20 includes the gage-scales 37, 38, which have thereon notches 39. 40 designates the opening in the wing-scale 20 adjacent the printing point on the platen, and 41 the strip thereunder, which connects the two wings of said scale 20.

The wing-scale frame 22 is shown as having connected thereto channel-shaped brackets 42, which have thereon horizontal flanges 44 and 45, which are situated one above the other with spaces therebetween, and which have therein suitable apertures 50 serving as sockets for the legs 46 of the card-guide 21 to extend thereinto. The card-guide 21 has therein the apex 48, which bears against the platen, and it is preferably formed by bending to shape from a half round bar or wire, the rounded part of the wire being placed adjacent the platen, and its legs 46 may be sprung into position into said apertures or sockets 50 as shown in Figure 4.

40 To limit the extension of the legs 46 into said apertures or sockets 50, stops are shown as formed on said legs 46 in the shape of undulations or jogs 49. The brackets 42 with the flanges 44 and 45 and the double sockets 50 contained therein will hold the legs 46 of the card-guide 21 very securely against dislocation, and, during the operation of the machine, the reaction of the platen against the upper part or apex 48 of the card-guide 21 will tend to press the legs 46 in their sockets 50 against the front walls thereof and increase the frictional resistance to sliding of said legs 46 out of their sockets 50.

55 When in operation, the middle part 47 of the card-guide 21 will press the wing-scale 20 against the card, thereby assisting in holding the card to the platen. By making the card-guide of half round wire of relatively large radius, the advantage of lightness combined with stiffness is obtained, and, by applying the card-guide with the rounded side of the bar toward the platen, thereby causing the surface of the bar or wire to flare away from the platen, the ad-

ditional advantage is secured that the surface of the wire serves as a directrix for the edges of the advancing and returning card.

Variations may be resorted to within the scope of the invention, and portions of the improvements may be used without others.

Having thus described my invention, I claim:

1. In a typewriting machine, the combination of a platen, a carriage for supporting the same, a wing-scale frame in front of the platen, and means for holding a card to the platen, said means comprising a scale connected to said frame, vertical flanges on said frame, runways in said flanges, bearing rolls to fit said runways, thereby securing the frame against lateral displacement, combined with means for pressing said rolls against said vertical flanges, horizontal flanges secured to said frame in pairs, one above the other with spaces therebetween, sockets in said horizontal flanges, and a card-guide having legs extending each into a pair of said sockets, thereby being secured to said frame.

2. In a typewriting machine, the combination with a platen and a frame adjacent the front of the platen, of a card-holder including a length of resilient material bent to form a bow and including a finger intermediate the free ends thereof for engaging a card to hold the same against the platen, said free ends being bent to provide substantially parallel supporting legs, and socket-members mounted on said frame for receiving the supporting legs, the latter arranged to be sprung to position for entering said socket-members and being self-retaining therein, due to friction caused by the resiliency of the bow.

3. In a typewriting machine, the combination with a platen and a frame adjacent the front of the platen, of a card-holder including a length of half-round resilient material of relatively large radius bent to form a bow and including a finger intermediate the free ends thereof for engaging a card to hold the same against the platen, the rounded portion of the material facing the platen, said free ends being bent to provide substantially parallel supporting legs, socket-members mounted on said frame for receiving the supporting legs, the latter arranged to be sprung to position for entering said socket-members and being self-retaining therein, due to friction caused by the resiliency action of said bow, and undulations formed on said legs, said undulations providing stops engaging the socket-members whereby to determine the home position of the legs.

4. In a typewriting machine, the combination with a platen and a frame adjacent the front of the platen, of a card-holder including a length of half-round resilient mate-

rial of relatively large radius bent to form a bow, the intermediate portion of the bow being formed with a finger for pressing a card against the platen, the rounded portion of the material facing the platen, and a pair of plates fixed to said frame in spaced relation, said plates bent outward adjacent their upper and lower ends, the bent portions having perforations therein for the reception of the free ends of said bow in parallel relation, said free ends being sprung toward each other and then entered into the perforations, said free ends being self-retaining therein, due to the expanding action of the bow.

5. In a typewriting machine, the combination with a platen, a wing-scale-carrying frame adjacent the front of the platen, and means for pressing the wing-scale toward the platen to grip a card, of a card-holder

including a length of half-round resilient material, of relatively large radius bent intermediate the ends thereof to form a finger, the rounded portion of the finger pressing against the card at a point above the wing-scale to hold said card against the platen, said holder also having portions extending to the right and the left from said finger to engage the wing-scale and press thereagainst to assist said wing-scale in gripping the card, the free ends of the holder extending downwardly adjacent the front of the wing-scale to provide supporting legs, and socket-members mounted on said frame for the reception of said legs, said free ends being sprung toward each other and then entered into said socket-members, said ends being thereby self-retaining, due to the expanding action thereof.

ALFRED G. F. KUROWSKI.
